UNITED STATES PATENT OFFICE.

WALTER J. THURMOND, OF COLUMBUS, GEORGIA.

DESIGN FOR A FIREPLACE.

46,516.

Specification for Design.

Patented Oct. 6, 1914.

Application filed June 8, 1914. Serial No. 843,889. Term of patent 7 years.

To all whom it may concern:

Be it known that I, WALTER J. THURMOND, citizen of the United States, and a resident of Columbus, in the county of Muscogee and State of Georgia, have invented a new, original, and ornamental Design for Fireplaces, of which the following is a specification, reference being had to the accompanying drawing, forming part thereof.

Figure 1 is a perspective view of my improved fire-place; Fig. 2 is a front elevation thereof; and Fig. 3 is an end elevation of the same.

Referring more particularly to the drawings, it will be seen that I have designed a fire-place which is constructed of metal or other suitable material, shaped to resemble a mantle and given the particular ornamental configuration shown.

I claim:

The ornamental design for a fire-place, as shown and described.

WALTER J. THURMOND.
